UNITED STATES PATENT OFFICE

2,506,327

ARTICLE OF TUNGSTEN AND WROUGHT COPPER JOINED BY SINTERED COPPER

Richards H. Harrington, Schenectady, N. Y., assignor to General Electric Company, a corporation of New York

Application January 18, 1947, Serial No. 722,798

1 Claim. (Cl. 250—149)

1
The present invention comprises composite metal bodies consisting of members of refractory metal and copper joined in good heat-conducting relation and thereby being adapted for use as targets in X-ray devices.

Target electrodes or targets as heretofore fabricated have consisted of a charge-receiving plate of a refractory metal, for example, tungsten, imbedded in a backing plate of cast copper which functioned as a means for carrying away heat generated by the impingement of high velocity electrons on the tungsten plate during the functioning of such target electrodes.

In some forms of high-powdered X-ray devices a member of tungsten united with cast copper has constituted both a discharge-receiving electrode and a wall-member in the evacuated envelope in which the electron discharge for producing X-rays was caused to operate. In such devices, it was found that leakage of gas occurred through wall members which interfered with the proper functioning of the devices and in many cases caused complete failure.

The entry of gas from the exterior into the evacuated space appears to be due to slow molecular diffusion of gas, ordinarily air, along the very slightly open grain boundaries characteristic of interdendritic shrinkage which occurs in some degree in all forms of cast or resolidified metal, the gas thereupon diffusing around the tungsten target into the evacuated space.

As a consequence of my present invention I have provided an improved composite body of tungsten and copper through which such diffusion of gas can not occur. In accordance with my invention composite metal articles are constructed of tungsten or other refractory metal joined to a body of wrought copper by an intermediate layer of finely divided copper consolidated under heat and pressure into a homogeneous sintered condition which is free from leakage paths. In the preferred embodiment of my invention a plate of forged copper is united externally to the copper which is consolidated from the powder state and which functions as a bonding layer between the plate of refractory metal and the plate of forged copper.

My invention is illustrated by the accompanying drawing in which Fig. 1 is a side elevation of a high voltage X-ray outfit in which a target assembly of my invention is embodied; Fig. 2 is a sectional view of a preferred form of target and Fig. 3 is a sectional view of an apparatus which is suitable for fabricating a composite target.

Leakage of gas into the evacuated space within

2
an X-ray apparatus has been found to be particularly troublesome in high voltage, high powdered X-ray devices, such as shown for example in Fig. 1, and described in detail in Charlton and Westendorp U. S. Patent 2,144,524, patented January 17, 1939. In such apparatus an extension tube 1 leads from the main evacuated chamber 2 and is terminated by a wall member which functions also as target. A source of cathode rays (electrons), as for example, an incandescent filament (not shown in the drawing) is provided in the main chamber. A beam of electrons, which may be suitably focussed by well understood means, is directed upon the end wall 3 of the X-ray apparatus. The impact of the electrons on the target generates X-rays which pass through the target and are radiated to the exterior. It is important, therefore, that the target should be as thin as practicable.

10 As indicated in Fig. 2 the target consists of a plate 4 of highly refractory metal, as for example, tungsten to which is joined a layer 5 of copper which is consolidated from a finely divided or powdered state by heat and pressure, as will be explained in connection with Fig. 2. As shown in Fig. 3 the consolidated copper powder preferably is joined externally to a plate 6 of wrought (cold worked) copper. In some cases the plate 6 may be omitted.

15 Cold worked, or annealed, copper does not have the slightly open grain boundaries characteristic of cast copper and hence is impervious to the molecular diffusion of gas from the atmosphere into the vacuum chamber.

20 Hot pressed or sintered copper when fabricated under the best methods of control approaches the density and gas-imperviousness of worked metal as an ultimate limit. Hence, hot-pressing under ideal conditions will provide a structure which

25 is sealed against leakage but for most practical purposes it is desirable to unite with the hot-pressed copper an outer barrier 5 of cold-worked (wrought) copper as a guarantee against leakage under ordinary factory methods of production.

30 Although the hot-pressing of copper is a known metallurgical procedure I have shown diagrammatically in Fig. 3 an apparatus for carrying out the fabrication of a composite target by hot-pressing.

35 A mold 7 of graphite, Fig. 3 is charged with a plate 6 of cold-worked copper upon which is superimposed a layer 8 of powdered copper and in turn a plate 9 of tungsten, or other chosen refractory target metal. In some cases the copper

plate 6 is omitted. Upon these metal layers is placed a graphite plunger 10. The mold 7 and its contents are heated to a sintering temperature, for example, to a temperature of about 1,000 to 1,050° C. The required heat conveniently is supplied electrically by passage of current supplied through water-cooled terminals 11, 12 which, as conveniently indicated, are connected to electric conductors 13, 14, carrying suitable current. Pressure is applied as indicated by the arrow upon the powdered copper whereby the copper plate 6 the copper powder layer 8 and the refractory plate 9 are united into a gas-impermeable unitary structure.

As shown in Fig. 2 the resulting composite plate is joined to the end walls of the extension tube 1 and forms the end closure 3 which functions as a target.

What I claim as new and desire to secure by Letters Patent of the United States is:

An X-ray device comprising an evacuated envelope and an X-ray target, said target con-

sisting of a plate of tungsten, a plate of wrought copper and an intermediate layer of sintered copper uniting said plates in good heat conducting relation, said plate of wrought copper forming a wall portion of said envelope.

RICHARDS H. HARRINGTON.
